CLAIM

The ornamental design for a container closure cap, as shown and described.

DESCRIPTION

FIG. 1 is a top perspective view of the container closure cap of my new design;

FIG. 2 is a bottom perspective view of the container closure cap of my new design;

FIG. 3 is a reduced top plan view of the container closure cap of my new design;

FIG. 4 is a reduced bottom plan view of the container closure cap of my new design;

FIG. 5 is a reduced rear elevational view of the container closure cap of my new design;

FIG. 6 is a reduced left-side elevational view of the container closure cap of my new design; and,

FIG. 7 is a reduced right-side elevational view of the container closure cap of my new design.
